CLEARER ROLL FOR SPINNING FRAMES

John Green Kershaw, Westmount, Quebec, Canada, assignor to Dominion Textile Company Limited, Montreal, Quebec, Canada, a corporation of Canada

Application April 14, 1942, Serial No. 438,934
In Canada October 1, 1941

6 Claims. (Cl. 19—140)

This invention relates to cloth covered clearer rolls for spinning frames and other textile machines.

Objects

It is a principal object of the invention to provide a structure for a cloth covered clearer roll wherein in the cloth covering is affixed in such a way as to prevent wear.

It is a further object of the invention to provide a roll of this nature including, in addition to the cloth covering, bearing surfaces permitting the roll to rotate in sliding contact with bearings.

With these and other objects in view, the invention embodies a roll including a cylindrical foundation or form on which the cloth is mounted and over the ends of which it is inturned and members cooperating with the form to retain the ends of the cloth in their inturned position. The roll may be provided with spaced apart collars of a smooth wear-resistant material serving as friction-free journals on which the roll may rotate, against stationary bearings.

Drawing

The invention will be better understood by reference to the accompanying drawing in which a preferred form is illustrated and in which:

Figure 1 is a fragmentary elevation of a clearer roll constructed according to this preferred form.

Figure 2 is a longitudinal cross section through the roll shown in Figure 1.

Referring in further detail to the drawing, this roll is made up of a central tubular foundation section or form 9 and similar end forms 10. The central and end forms are connected by plugs 11. Each plug 11 includes end portions of increased diameter forming annular shoulders 12 adapted to fit snugly in the ends of the forms 9 and 10, and midportions 13 of reduced diameter.

Two layers 20 of cloth are mounted on the forms 9 and 10. The outer ends 21 of the cloth 20 are tucked in about the ends of the forms 10 and held in place by a mushroom-shaped plug 25. This plug includes a stem 26 extending within the form 10 and engaging the ends 21 and a head 27 bearing against the end of the forms 10.

The ends 30 of the cloth adjacent each plug are also inturned over the ends of the forms 9 and 10 and the top of the shoulder 12. The ends 30 are held in place by a smooth-surfaced collar 35 encircling the narrow portion 13 which pinches the ends between it and the ends of the forms 9 and 10 and the shoulders 12.

The collars 35 may be of any suitable smooth-surfaced and hard-wearing material adapted for slideable contact with a bearing. The applicant has found lignum vitae particularly suitable.

5 The collar 35 is usually formed in two semi-circular mating halves which are adhesively secured together at their abutting ends and to the surfaces of the plug 13.

When a bearing surface is not needed centrally 10 on the roll, the collars 35 may be dispensed with and merely the end structure, namely, the plugs 25 used. In this case, the tubes 10 and cloth covering 20 run the full length of the roll and pegs of steel would be inserted in the plugs, 15 to serve as trunnions for journaling the roll.

Operation

In operation, the cloth covered roll, in the case of the preferred form shown, runs with the 20 collars 35 sliding on respective bearings and the cloth portion in contact with the roll which it is designed to clear.

In the case of ordinary forms of roll in which the collars 35 are omitted, the roll will be held 25 in contact by springs supporting the pegs in the ends.

In a structure such as this, the ends of the circular braided cloth tube are neatly tucked in and held in place so that they will not fray. The clearer roll is thus more desirably covered than 30 one covered in the usual way.

Method of construction

According to a preferred construction, the cloth 35 covering 20 is a braided tube of cotton or other suitable fabric, normally slightly oversize in respect to the diameter of the cylindrical form to which it is to be applied. This cotton tube is worked on to a metal cylinder of larger diameter than the clearer roll form on which the cloth is to be mounted, adhesive is applied to the form and the latter slipped within the cylinder. The cylinder thus intervenes the cloth tube and the 40 metal form.

The cylinder is slipped from between the tube and the form, leaving the tube on the form. The tube is then smoothed out from a central point. Its braided construction permits it to contract in 50 the transverse diameter as it lengthens, thus bringing it down in size to the external diameter of the form to which it is affixed by the adhesive.

The plugs and collars are then put into place to secure the ends on the form and the assembly 55 placed to one side for the adhesive to set, then

the clearer roll is ready for use on a spinning frame or other textile machine.

The use of this clearer roll with a spinning frame or other textile apparatus will be clear to one skilled in the art. Its use in a spinning frame is described in a copending application, Serial No. 438,933, filed April 14, 1942.

It will be understood that various modifications may be made in this invention without departing from the spirit thereof or the scope of the claims, and therefore the exact forms shown are to be taken as illustrative only and not in a limiting sense, it being desired that only such limitations shall be placed thereon as may be imposed by the state of the prior art or are set forth in the accompanying claims.

I claim:

1. A clearer roll for spinning frames, comprising, a plurality of tubular forms, a plug extending between adjacent forms and spacing them apart, said plugs each including an annular channel between the adjacent forms, said forms having a cloth covering, the ends of said covering projecting and being inturned over the ends of said forms, a smooth-surfaced collar encircling each plug in the channel thereof constituting a journal for the roll, said collar engaging said inturned ends between it and the ends of the respective forms.

2. A clearer roll for spinning frames, comprising, a tubular form, an integral cloth cover mounted on said form and having its ends inturned about the ends of said form, a plug inserted in the end of said tubular form to engage the ends of said cover, said plug being substantially mushroom-shaped, a stem portion on said plug extending within the form and engaging the ends of the cloth between it and the form, the head portion of said plug abutting the end of the roll and engaging the inturned ends of the cover between it and the end of the form.

3. A clearer roll, comprising, a cylindrical form, a plurality of annular channels in said form, a collar of hard bearing material in each channel constituting a journal adapted for sliding contact with a bearing, textile material surfacing other portions of the form and having ends adjacent the collars, ends of the textile material being engaged and held in place by the

collars, the textile-surfaced portions being adapted to perform the clearing function.

4. A clearer roll, comprising, a plurality of tubular forms, a plug extending between the ends of adjacent forms and connecting them together, clearing material surfacing each form to constitute clearing portions, smooth bearing material surfacing each plug to constitute annular journals adapted for sliding contact with stationary bearings, the bearing material abutting the ends of the clearing material and holding it in position, the surfaces of the bearing material being inset slightly from the surfaces of the clearing material thereby to form a relatively uniform diameter of the roll throughout its length.

5. A clearer roll, comprising, a plurality of tubular forms, a plug extending between the ends of adjacent forms and connecting them together, an annular channel in each plug, a collar of smooth bearing material in each channel constituting an annular journal adapted for sliding contact with a fixed bearing, textile material surfacing the forms and projecting over the ends thereof to be engaged by said collars, said textile material also projecting over the free ends of the forms, means connected to the free ends of the forms for retaining the projecting ends of the textile material.

6. An elongated clearer roll, comprising, a plurality of relatively extensive clearing portions and a plurality of relatively narrow journal portions intervening said clearing portions, said journal portions being spaced apart from each other and from the ends of the roll whereby the clearer roll is adapted to be journaled intermediate its ends, each journal portion being surfaced with smooth hard material inset slightly from the surfaces of said clearing portion and constituting a journal, the surfaces of said clearing portions being surfaced with clearing material, an end member on each end of said roll, the ends of said clearing material abutting said journal and said end members and being held in place thereby, each end member having a continuous smooth surface effective to inhibit the collection of fly.

JOHN GREEN KERSHAW.
